UNITED STATES PATENT OFFICE

ELMER V. RICE, OF COVINA, CALIFORNIA

SPIKED SANDAL

Application filed March 31, 1932. Serial No. 602,229.

My invention relates to an athlete's sandal adapted to be worn over an ordinary shoe and provided with the usual anti-slipping calks or spikes extending down from the sole of the sandal.

It is an object of this invention to provide a light flexible yet durable sandal which may be quickly slipped over the sole and forward portion of the upper of the ordinary shoe and provided with attaching means.

The present invention contemplates a construction of a sandal which covers the sole and the forward portion of the upper of the shoe only leaving the shank and heel portions of the shoe free. This type of sandal of the prior art was objectionable for the reason that sand, mud and other matter would work between the sole of the sandal and the sole of the shoe.

The present invention has for its object to provide means which will form a closure between the two soles preventing the entrance of any sand, water and the like. For this purpose a flexible strip of material, such as rubber, is secured to the inner end of the sole of the sandal which normally projects upwardly therefrom but when the sandal is slipped over the shoe the strip of rubber will form a closure between the two soles.

Another object of the invention is to provide a reversible strap whereby the sandal may be secured to the shoe and the buckle of the strap may be disposed either on the inside or outside of the shoe as desired by the user.

Another object of the invention is to provide anchoring means holding the strap against vertical displacement on the heel of the shoe.

With the above and other objects, which will appear as the description proceeds, my invention consists in the construction and arrangement of parts hereinafter described and claimed.

Referring to the drawing which forms a part of the specification:

Fig. 1 is a perspective view of a sandal containing my improved construction applied to a shoe.

Fig. 2 is a vertical longitudinal section through the sandal, showing the same applied to a shoe.

Fig. 3 is a top plan view of the sandal.

Fig. 4 is a vertical section of a spring hook and strap taken on the line 4-4 of Figure 3.

Fig. 5 is a detailed vertical section taken on the line 5 of Figure 3.

Referring to the drawing, 1 indicates a flexible outer sole, such as a leather sole, to which spikes 2 of any desired construction are secured. 3 indicates the inner sole to which the tip and vamps 4 are secured. The tip and vamps are preferably made of one piece of leather or the like and cover the forward part of the shoe S, to which it is secured by means of two straps, the front strap 5 and the rear strap 6.

The sole 1 of the sandal covers the sole of the shoe S, extending rearwardly to a line where the shank of the shoe turns upwardly. It is at this point where the slip-over sandals of the prior art were defective for the reason that dirt, sand, mud and the like, would work in between the sole 1 of the sandal and the sole of the shoe S. It is at this point where the sole 1 of the sandal terminates where the flexing of the shoe takes place, making an opening into which sand and the like would penetrate and work forwardly under the sole of the shoe. To overcome this difficulty I have provided a flexible strip 7, preferably made of rubber, and provided with reinforcing ribs 7', which is suitably secured to the inner end of the sole 1 of the sandal, such as by sewing, or vulcanization, or both. The strip 7 normally projects vertically upward therefrom, as shown in Figure 5, but when the sandal is slipped over the shoe and in use it snugly hugs the shank of the shoe as shown in Figure 2.

The upper 4 has a spring hook 8 secured by rivet 9 to opposite sides thereof for the reception of the reversible strap 6 which is provided with a buckle 10. One end of the strap 6 is provided with an eyelet 11 which snaps into the spring hooks 8 so that the buckle 10 may be disposed on the inside or

the outside of the sandal to suit the convenience of the wearer. A slidable sleeve 12 is arranged on strap 6, said sleeve being provided with an inwardly extending sharp point 13. When the strap 6 has been fastened and adjusted, the point 13 is pressed into the shoe above the heel, thus keeping the strap 6 in position and preventing vertical displacement thereof.

10 My improved sandal is especially suited for hiking, golfing and other athletic sports. It is light, flexible, hugs a shoe closely, and prevents the entrance of sand and the like between the soles of the sandal and the shoe. 15 It should also be noted that the tip and vamps are made of one piece and extend sufficiently far upward on the instep so that sand and dirt are prevented from getting between the vamp of the sandal and the upper 20 of the shoe.

Various changes may be made in the construction and arrangement of parts by those skilled in the art without departing from the spirit of my invention as claimed.

25 I claim:

1. A sandal comprising a flexible sole provided with antislipping members, means to removably attach the sandal to the forward portion of an ordinary shoe, said means comprising a pair of spring hooks attached to the shoe, and a reversible strap provided at one end with a link and at the other end with a buckle whereby said strap may optionally engage either of said spring hooks.

30 2. A sandal comprising a flexible sole provided with antislipping members, means to removably attach the sandal to the forward portion of an ordinary shoe, said means comprising a pair of spring hooks attached to the shoe, and a reversible strap provided at one end with a link and at the other end with a buckle whereby said strap may optionally engage either of said spring hooks, said strap having a slidable sleeve provided 35 with an inwardly projecting point to secure the strap against vertical displacement to the heel of the shoe.

40 In testimony whereof I have signed my name to this specification.
